United States Patent Office.

I. C. PENNINGTON, OF PATERSON, NEW JERSEY.

Letters Patent No. 90,778, dated June 1, 1869.

IMPROVEMENT IN STEAM-GENERATOR FURNACES.

The Schedule referred to in these Letters Patent and making part of the same.

To all whom it may concern:

Be it known that I, I. C. PENNINGTON, of Paterson, in the county of Passaic, and State of New Jersey, have invented a new and useful Improvement in Boilers and Furnaces; and I do hereby declare that the following is a full, clear, and exact description thereof, which will enable others skilled in the art to make and use the same, reference being had to the accompanying drawings, forming part of this specification, in which—

Figure 1 is a vertical cross-section of a boiler with which my improvement has been connected, taken through the line *x x*, fig. 2.

Figure 2 is a vertical longitudinal section of the same, taken through the line *y y*, fig. 1.

Similar letters of reference indicate corresponding parts.

My invention has for its object to economize the use of fuel used in heating steam-boilers, and reverberating and other furnaces, by using the heat escaping with the products of combustion, for heating the air, to support combustion, before it is introduced into the fire-box; and

It consists in the peculiar arrangement of parts, as will be hereinafter more fully described.

A represents the fire-box, which is provided with doors, for the admission of the fuel, for the admission of the tools for stirring the fire, and for the removal of the ashes from the ash-pit.

B is the grate, which I prefer to make in the form of steps or shelves, and which may be made of any suitable material.

From the fire-chamber *A*, the products of combustion pass through the boiler *C*, or over the hearth of the furnace, where they do their work, and pass thence

to the flue *D*, through which they pass to the chimney-flue *E*.

The flue *D* is enlarged, so as to form a chamber, in which is placed a series of pipes, *F*, the forward ends of which are supported by the plate *G*, which separates the flue *D* from the fire-chamber *A*.

The rear ends of the pipe *F* are supported by the plate *H*, that separates the flue *D* from the air, the outer ends of the pipes *F* thus opening into the open air, and their inner ends opening into the fire-box *A*.

By this construction, as the air passes, through the pipes *F*, to the fire-box *A*, to support the combustion of the fuel, it is heated by the products of combustion, which surround the said pipes, as they pass through the enlargement of the flue *D*, so as to utilize the heat that may be contained in said products of combustion, and return it to the fire-box *A*, in the heated air, thus retaining and utilizing the heat that would otherwise escape into the chimney.

The particular form of the enlargement of the flue *D*, and the position of the pipes *F*, will depend upon the kind and form of the boiler and furnace to which the improvement is applied.

Having thus described my invention, I claim as new, and desire to secure by Letters Patent—

The arrangement of the air-pipes *F*, supported by the plates *H G*, with reference to the enlarged flue *D*, chimney-flue *H*, boiler *C*, and fire-box and grate *A B*, as herein set forth and shown.

I. C. PENNINGTON.
